UNITED STATES PATENT OFFICE.

EDDIE H. HAMILTON, OF WASHINGTON, DISTRICT OF COLUMBIA.

PULLEY-PLATE.

1,346,747.

Specification of Letters Patent. Patented July 13, 1920.

Application filed November 25, 1919. Serial No. 340,590.

To all whom it may concern:

Be it known that I, EDDIE H. HAMILTON, a citizen of the United States, residing at Washington, in the District of Columbia, have invented new and useful Improvements in Pulley-Plates, of which the following is a specification.

This invention relates broadly to casement draperies.

10 An object of the invention is to provide, in combination with a drapery supporting pole, pulley plates which have trained around the pulleys thereof the strands of a cord or like flexible element, which is connected to the rings on the pole that support the confronting edges of the draperies, and whereby a pull on one of the strands will draw the draperies away from each other and a pull on the other strand will draw the 20 draperies toward each other.

A further object of the invention is to provide means which may be attached to any ordinary construction of drapery pole supports whereby the draperies may be adjusted with 25 respect to each other without necessitating the handling of the said draperies.

It is a further object to produce a pulley plate designed for use in connection with drapery pole supports, that shall be of a 30 simple nature, cheaply manufactured and marketed, easily applied, and thoroughly efficient for the purpose devised.

In the drawings:—

Figure 1 is a front elevation of a casement illustrating the application of the improvement.

Fig. 2 is an approximately central vertical longitudinal sectional view through one of the drapery pole supports and through one 40 of the pulley plates which is attached to the said support.

Fig. 3 is a perspective view of one of the pulley plates.

Fig. 4 is a similar view of another pulley 45 plate.

Fig. 5 is a sectional view, approximately similar to Fig. 2, but illustrating an angle pole support and a slight modification of the pulley plate.

50 In the drawings the numeral 10 designates a casement frame. Between the sides and adjacent to the top of the frame 10 there is supported a drapery carrying pole 29. This pole has its ends received in sockets 28 that 55 are provided with interior threads to engage with the exterior threads on bosses 27 that

are carried by plates 25. The plates 25 have openings 26 therethrough for the reception of securing elements. The foregoing construction is common to the art, but in connection with my improved pulley plates, hereinafter to be described I employ a flexible pull element such as a cord and attach the same to the confronting ends of the rings 30 and 31 which are attached to the inner ends of the 65 draperies (not shown).

Of course other rings are arranged on the pole and are also attached to the draperies.

The pair of pulley plates which I employ for each curtain pole support are of a similar construction, and therefore the reference characters indicating the parts of one may be understood as equally applicable to the other. The pulley plates are indicated by the numerals 11 and 12 respectively. 70 Each pulley plate is constructed, preferably, from a single piece of material, metal preferred, and bent or otherwise formed to provide parallel spaced members 13 and 14 which, in the construction illustrated in 75 Figs. 3 and 2 have their confronting edges provided with a central reduced strip, and this strip is bent laterally to provide upper and lower spaced members 15 and 16 and an 80 end connecting portion 17 therefor. The 85 ends of the spaced members 13 and 14 are thus provided with an open foot portion, and journaled therein is a pulley wheel 18.

In the construction illustrated by Fig. 4 the foot portion for the offset ends 15 and 16 90 of the members 13 and 14 are arranged in contacting engagement and the outer end thereof is rounded upon itself, as at 19 to provide a bearing for a shaft 21 on which is journaled a pair of spaced pulleys 22. The 95 foot portion of the member 12 is slotted both longitudinally and transversely and the material bounded by the slits is bent outwardly to provide stop members 20 which hold the pulleys 22 out of contacting engagement 100 with each other.

The front and rear portions, or plates 13 and 14 of the members 11 and 12 have, at their upper ends, round openings 23 which receive therethrough the bosses 27 on the 105 pole supporting plates 25. These bosses are passed through the openings by bending one of the plates, say the plate 14 away from the plate 13 after the body plates 25 of the pole supports have been arranged between 110 the plates 13 and 14 of the members 11 and 12. It should here be stated that the mem-

bers 11 and 12 are preferably constructed of spring material. When the bosses are passed through the openings in the members 11 and 12, the socket members 28, which 5 may have been previously arranged on the pole 29 will be brought to threadedly engage with the bosses and contacting with the outer plates 14 force the same toward the plates 13 to tightly grip the body plates 10 25 between the said plates 13 and 14. The outer plates 14 may be provided with elongated slots 24 so that the lower opening 26 in the body plates 25 may properly receive the lower securing elements 27 which also 15 pass through the slots 24.

The flexible pull cord has one of its strands 32 trained over one of the pulleys 22, knotted, as at 33, to the ring 30 and is 20 from thence passed around the pulley 18 of the member 11, knotted to the ring 31, as indicated by the numeral 34, passed over the second pulley 22 and terminating in a second pull cord 35. It will be apparent that when a downward pull is exerted on the 25 strand 32 the ring 30 will first be drawn toward the ring 31, and thereafter the ring 31 will be drawn toward the ring 30, thus bringing the confronting edges of the draperies toward each other. A pull on the 30 strand 35 will first draw the ring 31 away from the ring 30, and thereafter draw the ring 30 away from the ring 31, thus causing the parting of the draperies.

In Fig. 5 the pulley plate, 36 has a foot 35 portion in which a pulley or pulleys are journaled and a body comprising spaced plates 37 and 38. Both of the plates are provided with alined round openings 39. Between the plates is received the body 40 plate or member 40 of the curtain pole supporting bracket. The supporting bracket has an angular base 41 provided with openings 42 for the attaching nails or screws. The pulley plate 36 may be reversely positioned on the supporting bracket, that is the 45

boss 43 on the plate 40 may be passed through either opening 39 in either the plate 37 or 38. The boss is threaded and is engaged by the interior threads on a socket member 44 that receives one end of the 50 drapery pole.

Having thus described the invention, what I claim is:—

1. In combination with a drapery pole support comprising a plate having a 50 threaded boss thereon and a threaded socket engaging with the boss to receive the end of the pole; of a pulley plate comprising two spaced resilient members having an opening therethrough to receive the boss when the 60 members are spread apart previous to the application of the socket on the boss and received between the said members, said socket when screwed upon the boss designed to contact with one of the said members, 65 said members having an offset foot portion and pulleys journaled therein.

2. In combination with a two piece drapery carrying pole and support for the ends thereof, the latter including each a plate 70 having openings for securing means, a threaded boss and a removable interiorly threaded sleeve designed to engage with the boss; of pulley carrying members, each including spaced plates having openings 95 therethrough designed to receive therebetween the body plate of the support and to have passed through the said openings the boss portions of the supports, said members having elongated slots therethrough registering with the lower openings in the body plates of the supports, offset feet on the lower portions of the members, pulley wheels carried thereby, and a flexible element trained around said wheels and connected to the confronting edges of the draperies, as and for the purpose set forth. 80 85

In testimony whereof I affix my signature.

EDDIE H. HAMILTON.
